RAIL ANCHOR SHIPPING BUNDLE

Harold G. Warr, Park Ridge, Ill., assignor to Poor & Company, Chicago, Ill., a corporation of Delaware

Application November 16, 1942, Serial No. 465,737

9 Claims. (Cl. 206—65)

This invention relates to certain new and useful improvements in bundles suitable for shipping rail anchors and particularly rail anchors of one piece construction.

There are many forms of one piece rail anchors disclosed in prior patents and there are several forms now being made and sold. While these various forms may differ in regard to specific constructions, their general constructions, with the possible exception of one or two known forms of devices, include two principal features, to wit: an under-rail portion formed at one end with a hook shaped jaw adapted to engage over one flange of a rail base. Most forms of one piece rail anchor devices also include a locking means such, for example, as a shoulder or a jaw for engaging the other flange of the rail base.

Heretofore it has been customary to ship rail anchor devices of the above general type in burlap bags, said bags being heretofore obtainable at moderate price and were usable as shipping containers, but they were not entirely satisfactory. For example, the size and construction of the anchor devices cannot be determined without first opening the bag for examination. If one or more bags of anchors of the wrong form or size should be accidentally included in a shipment, such error cannot be detected until the bag reaches its destination and is opened by the track-crew for distribution along a track or for application to the rails. Furthermore, the hook-jaw portions of anchor devices of the character mentioned when shipped in loose, non-orderly arrangement, frequently become entangled with each other in such manner as to be difficult to separate.

An object of the present invention is to overcome the above and other difficulties encountered in connection with the use of burlap bags as shipping containers. In this connection the invention includes the provision of a bundle in which the anchor devices are so arranged that their construction, size and number can be determined at a glance and which will maintain the anchor devices in orderly arrangement.

Another object is to provide a compact bundle of rail anchor devices which may be readily and conveniently handled by workmen without undue exertion and which will stand severe shocks, such as dropping during the handling or stacking of the same for storage or shipment, without danger of displacement of the anchor devices with relation to each other in the bundle.

A further and more specific object of the invention is to provide a shipping bundle assembly in which rail anchor devices are arranged in a plu-

rality of tiers or courses and the said tiers are so secured together as to hold each anchor in relatively fixed position in the bundle.

A further object is to provide a bundle assembly in which the anchors are so arranged as to facilitate forming the bundle by means of automatically actuated machinery and thereby minimize the amount of labor required in forming the bundle.

Other objects and advantages of the invention will become apparent from the detailed description hereinafter given of the approved forms of bundles hereinafter shown by way of examples.

In the drawings:

Fig. 1 is one approved form of bundle assembly for rail anchors.

Fig. 2 is a view of the top portion of the bundle illustrated in Fig. 1 with parts of the securing means broken away so as to show an interlocked arrangement of the upper and lower tiers of anchor devices.

Fig. 3 is an end view of the bundle assembly as shown in Figs. 1 and 2 and illustrating the manner in which the jaw members of the anchor devices fit over and have frictional engagement with supporting frame members.

Fig. 4 is a fragmentary sectional view taken on line 4—4 of Fig. 1 to further illustrate the interlocking relation of the anchor devices.

Fig. 5 is a view similar to Fig. 1, but illustrating a different form of anchor device; and

Fig. 6 is a view similar to Fig. 3 but showing the form of anchor device illustrated in Fig. 5.

The particular forms of rail anchor devices illustrated herein are shown merely for the purpose of illustration. While certain specific features of the invention may apply especially well in some respects to the form of anchor shown in Figs. 1 to 4 inclusive and in other respects to the form of anchor shown in Figs. 5 and 6, the invention is not intended to be restricted to the use of the particular forms of rail anchors shown and described, but is intended broadly to cover bundles composed of any form of rail anchor device having a jaw adapted to be fitted over and frictionally engage a supporting frame in the manner herein disclosed and claimed.

Referring first to the bundle illustrated in Figs. 1 to 4 inclusive: The construction of the rail anchor shown therein may be more readily understood by reference to Fig. 3. It includes a bar T-shaped in cross-section and bent at one end into hook form, as shown at 10. The other end of the bar is offset to form a shoulder 11. The bending of the hook portion is such that the centrally disposed flange or stem 12 of the T cross-

section of the bar follows in a general way the curvature of the jaw. The end portion of the hook is formed with an inclined surface 13 which inclines at substantially 14° relative to the plane of the surface 14. During the bending of the hook portion of the bar and also during the formation of the shoulder 11, the metal is displaced slightly laterally so that when a plurality of the anchor devices are arranged side by side, as indicated in Fig. 1, they will normally contact only at the lateral bulges adjacent the end 15 of the jaw, the end 10 of the jaw and the locking shoulder end 11.

The bundle illustrated in Figs. 1 to 4 inclusive comprises a series of rail anchor devices, designated as a group by the letter A, arranged side by side in the manner shown in Fig. 1 with the laterally bulged faces 10, 11 and 15 of one anchor in contact with similar portions of an adjacent anchor. A supporting frame member 16, wedge shaped in cross section, fits tightly in the bite of the hook jaw portion of each anchor device. Preferably the member 16 is made of wood with its face F sloped to correspond substantially with the inclined inner face 13 of the jaw 10. The wedge shaped cross-section of the frame member 16 makes it practical to use one size of frame member for several sizes of anchor jaws. The wedging engagement of the wood frame in the bite of each anchor jaw effects sufficient frictional grip on the upper face of the anchor body and the inner surface of the jaw 10 to firmly hold the anchor in position on the frame. The said gripping action of the several anchor devices on the wood frame member also forms depressions in the wood which correspond to the width of the separate anchor devices and serve as further means for resisting lateral or other displacement of the anchors lengthwise of the frame member.

Another series of rail anchors, designated B, are similarly arranged on a like frame member 16a. The construction of the anchors of group B are the same as those of group A and are designated by the same reference numerals with the addition of the letter a. The two groups of anchors A and B are arranged so that the depending webs 17-17 of adjacent anchors of group A will extend into the space between the webs 17a-17a of adjacent anchors of the group B to provide interlocking engagement. The interlock of the specific form of anchor shown, it will be observed, is due largely to the seating of the curved lower edges of the rigidifying ribs 17 and 17a, as the case may be, of one group of anchors between the spaced apart edges of the anchor bodies of the other group; the said anchor bodies being held in such spaced relation by the bulges 10, 11 and 15 (see Fig. 1).

After the two tiers of anchor devices are arranged in their interlocked relation, as shown, a locking member 18 is positioned in the V-shaped space (see Fig. 3) defined by the curved outer surfaces of the hook ends of the opposing anchors. This locking member is preferably rectangular or otherwise formed with a portion 19 for extending into the V-shaped space previously defined. The said locking member is preferably made of wood of suitable hardness so that it will withstand the normal strains imposed in service. The opposite ends of the locking member 18 and likewise the opposite ends of the frame members 16-16a are provided with suitable grooves 20, 21 and 21a for receiving binding wires 22-22. Said binding wires are looped

about the ends of the members 16, 16a and 18 to bind these members tightly together in a general triangular arrangement and thereby bind firmly together the anchor devices. The ends of the binding wires are preferably united by means of twist connections 23-23. The position of the wires in contact with the anchor device at opposite ends of the bundle together with the grooves in the frame and locking members serve to prevent movement of any portion of the bundle lengthwise of the frame member.

Figs. 5 and 6 illustrate a modified arrangement of anchor devices of a different construction disposed in orderly arrangement to form a bundle similar to that described and shown in Figs. 1 to 4 inclusive.

In the modified embodiment the anchor devices are made from stock rectangular in cross-section. Each anchor comprises a bar bent at one end into hook configuration to provide upper and lower jaws 24-25. The body portion 26 is provided with a bowed configuration, substantially as indicated at 27, and the other end of the bar is formed with a locking shoulder. The shoulder has no particular function in the present bundle construction, but is adapted to snap over one edge of the rail base to hold the anchor device fixed to the rail.

The anchor devices are arranged in two series of groups, designated C and D. The hook end portions of all anchors in group C are fitted over and wedgingly engage the upper edge portion of a frame member 28. The frame member 28 may be, and preferably is, the same in construction as previously described frame member 16 except that the grooves 21 are formed in the lower edge only of the frame. The anchor devices of group D are similarly mounted on a wedge shaped frame member 28a and the two groups of anchors are arranged back to back, as shown in Fig. 6. A locking bar 29, preferably of rectangular configuration in cross-section, is seated with one of its edges wedging into the V-shaped portion defined by the oppositely curved hook portions of the opposed anchors. Binding wires 30-30 are then looped about the opposite ends of the frame members 28-28a and locking member 29. The said wire loops 30-30 fit into the grooves 21-21a of the frame members 28-28a and into the grooves 31 of the member 29. The binding wires 30-30 are arranged so that their portions designated 32, 33 and 34 will be in contact with surfaces of the anchor devices disposed at the ends of each series C and D, and therefore provide abutments for the anchor devices which will resist any tendency which the anchors might have to shift lengthwise of the frame members 28-28a. The ends of the wires 30-30 are connected by a twist connection 35, whereby the members 28, 28a and 29 are held bound tightly together in a general triangular arrangement and thereby bind firmly together the anchors of both groups C and D.

While the invention is illustrated in connection with two specific embodiments of rail anchor devices, it will be apparent that similar bundles may be formed with anchors of different constructions. It will be understood, therefore, that the claims accompanying this specification are not to be limited to the specific constructions herein shown and described except insofar as limitations may appear in the said claims.

I claim:

1. A rail anchor bundle comprising a group of

rail anchors arranged in parallel relation, each anchor having a body portion formed at one end with a hook, a frame member arranged transversely of the anchors and having a wedge shaped portion extending into the recesses defined by their hook portions to provide frictional engagement therewith, and means including a bar engaging the anchors at a location spaced from the frame and wire loop members connected therewith for holding said anchors in fixed position on said frame.

2. A rail anchor bundle comprising a group of rail anchors engaged in parallel arrangement, each having a body portion formed at one end with a hook, a frame member arranged transversely of the anchors and having a wedge shaped portion extending into the recesses defined by their hook portions to provide frictional engagement therewith, and means including a bar engaging the outer portions of said hooks and wire loop members connecting said bar with said frame so as to hold the anchors in fixed position on the frame.

3. A rail anchor bundle comprising a group of rail anchors arranged in parallel relation, each anchor having a body portion formed at one end with a hook, a frame member arranged transversely of said anchors and having wedging engagement in the hook portions of said anchors, a second group of anchors arranged in parallel relation and having portions of their outer surfaces engaging portions of the outer surfaces of the anchors of the first mentioned group, a frame member having wedging engagement in the hook portion of the second group of anchors, and binding means engaging the ends of said frame members to hold the anchor devices in position thereon and in frictional engagement with each other.

4. A rail anchor bundle comprising a group of rail anchors arranged in parallel relation, each anchor having a body portion formed at one end with a hook, a frame member arranged transversely of said anchors and having wedging engagement with the hook portions of said anchors, a second group of anchors arranged in parallel relation and having portions of their outer surfaces engaging portions of the outer surfaces of the anchors of the first mentioned group, a frame member having wedging engagement in the hook portion of the second group of anchors, and binding means comprising strands of wire engaging the ends of said frame members to hold said frames in firm relation to each other and to clamp the anchor devices in frictional engagement with each other.

5. A rail anchor bundle comprising a group of rail anchors arranged in parallel relation, each anchor having a body portion formed at one end with a hook, a frame member arranged transversely of said anchors having wedging engagement in the hook portion of said anchors, a second group of anchors arranged in parallel relation and having portions of their outer surfaces engaging portions of the outer surfaces of the

anchors of the first mentioned group, a frame member having wedging engagement in the hook portions of the second group of anchors, a bar positioned to engage corresponding outer surfaces of the anchors of both groups, and binding means extending around the end portions of the frame members and said bar to hold the anchor devices clamped in position.

6. A rail anchor bundle comprising a group of rail anchors arranged in parallel relation, each anchor having a body portion formed at one end with a hook and having a rigidifying rib extending outwardly from the said body and hook, a wood frame arranged transversely of said anchors and having wedging engagement in the hook portions of said anchors, a second group of anchors arranged in interlocked relation with the anchor bodies and ribs of the first group, and binding means engaging the ends of said frame members to hold the anchor devices in frictional engagement with each other.

7. A rail anchor bundle comprising two groups of rail anchors arranged back to back, each anchor having a body portion formed at one end with a hook and having a rigidifying rib extending outwardly from said body and hook, wood frame members extending lengthwise of said groups and having wedging engagement in the hook portions of the anchors of its associated group, a wood bar extending transversely of the anchors in the space defined by the diverging rib portions of opposing groups, and strands of binding wire drawn tightly around the end portions of the frame members and said bar to clamp the frame members in fixed relation and to clamp said bar firmly against the rigidifying rib portions of all anchors of the bundle.

8. A rail anchor bundle comprising two groups of rail anchors arranged back to back in parallel arrangement, each anchor having a bowed body portion and having a hook portion at one end of the body, wood frame members arranged transversely of the anchors and having wedging engagement in the hook portions of the anchors of each group, a wood bar extending transversely of the anchors in the space defined by the diverging surfaces of the hook portions of opposed anchor devices, and strands of binding wire drawn tightly around the end portions of the frame members and said bar to clamp the frame members in fixed relation and to clamp said bar firmly against the curved portions of said anchors.

9. A rail anchor bundle comprising a group of rail anchors arranged in parallel relation, each anchor comprising a bar, rectangular in cross section formed with an outwardly bowed body portion and provided at one end with a body with a hook shaped bend, a wedge shaped supporting frame inserted in and having wedging fit in the recess defined by the hook portion of each anchor, and means engaging the said frame member and said anchors for maintaining them in fixed position on the supporting frame.

HAROLD G. WARR.
